UNITED STATES PATENT OFFICE.

CARL BARTELS AND CLAYTON J. GOEBEL, OF HAMILTON, OHIO, ASSIGNEES TO THE
MOSLER SAFE COMPANY, OF HAMILTON, OHIO, A CORPORATION OF NEW YORK.

SAFE OR VAULT DOOR.

Application filed September 11, 1923. Serial No. 662,049.

This invention relates to safes and vaults, and more particularly relates to safe or vault doors, and especially to doors which are useful for emergency entrance.

5 The provision of emergency doors in safes and vaults is becoming more popular, due to the fact that there is an increased desire for means whereby access may be had to a safe or vault in case of emergency.

10 Emergency entrances are also desirable and useful for purposes of ventilation. It is desirable that an emergency door be burglar-proof, and yet be readily responsive in the hands of an authorized person, and at 15 the same time be reasonably inexpensive to construct and install in a safe or vault.

The principal object of our invention is to provide a safe or vault door which is burglar-proof, yet readily operable by an authorized person, and at the same time is comparatively inexpensive to construct and to install in a vault or safe.

A further object of our invention is to provide a door of the above character which is especially suitable for use as an emergency entrance to the safe or vault.

A further object of our invention is to provide novel and improved locking mechanism for the door.

30 Other objects of this invention will be in part obvious and in part pointed out hereinafter.

In accordance with our invention, we provide a circular door, preferably carrying 35 lock mechanism including combination and time features, the door being provided with a circular bolt-frame adapted to cooperate with a revolvable locking ring mounted on the vestibule, which ring, in accordance with 40 its position, locks and unlocks the door, and means are provided which are operable from the exterior of the door for moving the revolving locking ring on the vestibule into and out of locking position.

45 Heretofore, the standard type of emergency doors requires square frames or vestibules. Such frames involve more expensive construction than do circular frames. Moreover, in such constructions, the accessible means for operating the bolt-work mechanism has been located on the vestibule jamb. In our construction, such means are located on the door, thus eliminating the expense of locating these means
50 in the vestibule jamb.
55

In order that a clearer understanding of our invention may be had, attention is hereby directed to the accompanying drawings, forming a part of this application and illustrating one possible embodiment of our invention. 60

Referring to the drawings:—

Fig. 1 is a plan view of a door embodying our invention, showing a portion of the vestibule jamb with the door unlocked;

Fig. 2 is a sectional view of a part of the door and vestibule jamb, and is taken on the line 2-2 of Fig. 1;

Fig. 3 is a perspective view of a portion of the door and vestibule jamb, the door being unlocked; and

Fig. 4 is a perspective view of a fragment of the door, showing in full lines the locking dog in unlocked position, and showing in dotted lines the locking dog in locked position. 75

Similar reference characters refer to similar parts throughout the several views of the drawings.

On the rear of the door 1 are assembled 80
suitable combination lock mechanisms, dia-
grammatically shown at 2 and 3, and a time
lock mechanism, diagrammatically shown at
4. These lock mechanisms are connected to-
gether by a link 5, which in turn is con-
nected by a link 6 to the middle of a lever
arm 7, which is pivoted at one end to the
door, as at 8, and which at its other end, as
at 9, is pivoted to a locking lug 10. Locking
lug 10 is suitably mounted and guided in
the door, and its function is to prevent or
allow movement of a segment 11 from lock-
ing position to unlocking position. To this
end, segment 11 is mounted on the door for
slidable movement across an end of lug 10
when lug 10 is in retracted or unlocked posi-
tion, and the arrangement being such that,
when segment 11 is in locked position, lug
10 may be moved into locking position
across an end of segment 11. This will pre- 100

across an end of segment 11. This will prevent movement of segment 11 into unlocked position until lug 10 has been retracted to allow segment 11 to move by. Segment 11 is movable into and out of locking position from a hand-wheel 12, which is at the outside of the door, being mounted on the end of a shaft 13, which is journaled in the door, shaft 13 at its inner end having a pinion 14 which is constantly in mesh with teeth 15 provided on segment 11. Segment 1105 110

11 also carries a locking dog 16, which extends outwardly and is permanently engaged in a recess 17 provided therefor in one of the holding lugs 18, which constitute a part 5 of a locking ring 19. Ring 19 may be held revolvably in place on the vestibule 20 by turning out a rabbet 21 in the vestibule, and forming a retaining groove for the ring 19 by securing circular box plates, such as 22, 10 to the vestibule behind the ring 19. When locking ring 19 is moved to locked position, its lugs 18 are moved into locking engagement behind cooperating lugs 23 provided on the door, and when locking ring 19 is 15 moved into unlocked position, its locking lugs 18 align with recesses between the lugs 23 of the door, permitting the door to be opened. Suitable spring detents 24 may be provided in the vestibule jamb to yieldingly 20 maintain the locking ring 19 in adjusted position. To permit movement of locking dog 16 into and out of locking position, the bolt-frame 25 of the door is suitably slotted, as at 26.

25 In combination with the above, there may be provided a day-gate 27 and a glass frame 28 of usual constructions. The vestibule jamb 20 may be secured to the wall 29 of the vault or safe by any suitable means, and 30 about the front of the vestibule there may be provided an architrave 30, and at the rear of the frame there may be provided a flange bar 31.

35 The operation of the door and locking mechanism will be apparent from the above description. When the locking lug 10 is in unlocking position, as shown in Fig. 1, the door may be locked and unlocked by merely rotating the handle 12, on account of the 40 connection between pinion 14 with teeth 15 of segment 11, which in turn is in engagement with locking ring 18 through locking dog 16 and recess 17. When segment 11 has been removed into locking position through 45 operation of hand-wheel 12, movement of locking lug 10 into position across the end of the segment, by means of the combination or time lock mechanisms, will prevent the movement of segment 11 into unlocking position, either by means of hand-wheel 12 or otherwise, and will thus prevent the unlocking of the door until locking lug 10 has been retracted by the combination and time lock mechanisms.

50 As many changes could be made in the above construction, and as many various embodiments of this invention could be made without departing from the scope thereof, it is intended that all matter contained in the above description or shown in the accompanying drawings be interpreted as illustrative and not in a limiting sense.

What we claim is:—

1. The combination with a vestibule jamb 65 and a door fitting the jamb, of locking means

on the door, coating locking means movably carried on the jamb, and means carried on the door, for moving the locking means on the jamb when the door is closed into and out of locking coaction with the locking means on the door.

2. The combination with a vestibule jamb and a door fitting the jamb, of movable locking means carried on the jamb for locking the door in the jamb, means carried on 75 the door and movable into and out of operative engagement with the locking means as the door is closed and opened, for actuating the locking means when the door is closed, and means on the door for operating 80 said actuating means.

3. The combination with a vestibule jamb forming a circular jamb opening and a circular door fitting said opening, of a locking ring encircling said opening and movably 85 supported for rotation on the vestibule jamb, a handle on the door, and means on the door connecting said handle with said ring when the door is closed, whereby the locking ring may be rotated in the jamb by means of said 90 handle.

4. The combination with a vestibule jamb and a door, of a revolvable locking ring on the vestibule jamb, and having a recess, a movable dog on the door, adapted to lock 95 in said recess when the door is closed, and operable means for moving said dog to place said locking ring into and out of locking position when said door is closed.

5. The combination with a vestibule jamb 100 and a door, of a revolvable locking ring on the vestibule jamb, and having a recess, a movable dog on the door, adapted to lock in said recess when the door is closed, and operable means for moving said dog to place 105 said locking ring into and out of locking position when said door is closed, said means including an operating member carried on the door and accessible from the exterior thereof.

6. The combination with a vestibule jamb and a door, of a revolvable locking ring on the vestibule jamb, and having a recess, a movable dog on the door, adapted to lock in 110 said recess when the door is closed, and operable means for moving said dog to place said locking ring into and out of locking position when said door is closed, and means, controlled by lock mechanism and associated with said operable means, for preventing operation of said means to place 115 said ring from locking to unlocking position.

7. The combination with a vestibule jamb and a door, of a revolvable locking ring on 125 the jamb, and having a recess, a movable segment on said door and having a dog adapted to lock in said recess when the door is closed, and means for moving said segment to place said locking ring in locked and 130

unlocked position when the door is closed.

8. The combination with a vestibule jamb and a door, of a revolute locking ring on the jamb, and having a recess, a movable segment on said door and having a dog adapted to lock in said recess when the door is closed, and means for moving said segment to place said locking ring in locked and unlocked position when the door is closed, said means including a shaft journaled in said door and connected to said segment, and a handle on said shaft accessible from the front of the door.

9. The combination with a vestibule jamb and a door, of a revolute locking ring on the jamb, and having a recess, a movable segment on said door and having a dog adapted to lock in said recess when the door is closed, means for moving said segment to place said locking ring in locked and unlocked position when the door is closed, lock mechanism, and a movable locking lug mounted on said door, and controlled by said lock mechanism, and adjustable thereby into and out of locking engagement with said

segment, to prevent or permit movement of said segment to place said locking ring in unlocked position.

10. The combination with a vestibule jamb, of a circular slot in said jamb, a locking ring loosely mounted in said slot for rotative movement on said jamb, and spring detents in said jamb, engaging said ring, and yieldingly holding said ring in adjusted position.

11. In a safe, the combination with a door and door jamb, of stationary peripheral lugs on the door, an annular recess on the door behind said lugs, a movable locking ring on the jamb having lugs seating in said recess when the door is closed, and means on the door for rotating said locking ring when the door is closed to move the lugs of the locking ring into and out of locking engagement behind the lugs on the door.

This specification signed this 31 day of August, 1923.

CARL BARTELS.
CLAYTON J. GOEBEL.
